curved edge 18 and traversing the space between the portions 35, 36. It will be noted that at the upper end of each cup 12 are upwardly and inwardly inclined edges 46, 47 terminating at an apex 48. Stitched to the upper edges of the panels 13 and cups 12 is an ornamental binding 50.

Interconnecting the apices 48 with the ends of the panels 13 are shoulder straps 52. The shoulder straps may be provided with adjustable buckles 53 if desired, to adjust the length of the shoulder straps.

It will be noted that the cloth of which the edge portions 35, 36 are made is heavier, firmer, than the net cups 38a. Thus the portion of the net cups 38a between said portions 35, 36 is lighter and softer than the portions 35, 36 and furthermore is formed with openings through which air may readily pass. It will be noted that the portions of the cups 38a between the side portions 35, 36 extend from the bottom of the cups to the top of the cups. Thus the breasts of the wearer will be supported at the sides and will have light, soft, open net material at the middle extending from top to bottom. The brassière herein described is hence particularly adaptable for use when sleeping. Instead of the breasts being supported for uplift as with the usual brassières, the breasts will be supported against side movement, and furthermore "breathing" is permitted through the portion of the cups 38a between the reinforcing or firmer portions 35, 36, so that the brassière is comfortable and light in use. Thus with the present brassière although the breasts are retained in natural position, the wearer has the benefit of comfort during sleeping hours.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A brassière comprising a pair of cup portions, each of said cup portions having at the opposite sides thereof a pair of laterally spaced relatively rigid side portions and a relatively light, soft central portion between said side portions and extending from the top to the bottom of the cup portions, each of said relatively rigid side portions extending from the top to the bottom of the cup portion and from an extreme side thereof to said central portion.

2. A brassière comprising a pair of breast cups, each cup having at the opposite sides thereof a pair of laterally spaced side portions made of woven, textile cloth, and a central portion of net material between said side portions and extending from the top to the bottom of the cup, each of said woven textile side portions extending from the top to the bottom of the cup and from an extreme side thereof to said central portion.

3. A brassière comprising a central panel having a central upwardly extending portion and bottom outwardly extending portions, side panels attached at their inner ends to the outwardly extending portions of the central panel, and breast cups interposed between said central panel and the side panels, each cup having at the opposite sides thereof a pair of laterally spaced relatively firm side portions and a relatively soft central portion beneath said side portions and extending from the top to the bottom of the cup, each of said relatively firm side portions extending from the top to the bottom of the cup and from an extreme side thereof to said central portion.

4. A brassière comprising a central panel having a bottom edge and inwardly curved side edges forming an upwardly extending portion, and a pair of outwardly extending portions, a pair of side panels having inwardly curved upper edges and inwardly extending portions stitched to the outwardly extending portions of the central panel, cups stitched to the inwardly curved edges of said central and side panels, each cup comprising at the opposite sides thereof a pair of laterally spaced side portions of relatively heavier woven textile material, and a relatively light central portion of net material interposed between said side portions, and extending from the top to the bottom of the cup, each of said woven textile side portions extending from the top to the bottom of the cup and from an extreme side thereof to said central portion.

EDWIN H. WEGMAN.
